US00D981057S

(12) **United States Design Patent** (10) **Patent No.:** **US D981,057 S**
Bates et al. (45) **Date of Patent:** **** Mar. 14, 2023**

(54) **RFID TAG INSERTION CARTRIDGE**

(71) Applicant: **Somark Group Ltd.**, Sydney (AU)

(72) Inventors: **Alexander Jonathan Bates**, Christies Beach (AU); **Marco Antonio Cid**, Coromandel Valley (AU); **Louise Sian Thompson**, Morphett (AU); **John Joseph Kinson**, Aberfoyle Park (AU)

(73) Assignee: **SOMARK GROUP PTY LTD.**

(**) Term: **15 Years**

(21) Appl. No.: **29/701,974**

(22) Filed: **Aug. 15, 2019**

(51) LOC (14) Cl. **30-08**

(52) U.S. Cl.

USPC **D30/155**

(57) **CLAIM**

The ornamental design for an RFID tag insertion cartridge, as shown and described.

DESCRIPTION

FIG. 1 is a perspective view of a RFID tag insertion cartridge, according to our new design.

FIG. 2 is a right side view thereof;

FIG. 3 is a left side view thereof;

FIG. 4 is a bottom plan view thereof;

FIG. 5 is a top plan view thereof;

FIG. 6 is a rear view thereof;

FIG. 7 is a front view thereof; and,

FIG. 8 is another perspective view thereof, but shown in a state of use with a RFID insertion tool in an environmental view.

The broken lines shown in FIGS. 1 through 8 illustrate portions of the RFID tag insertion cartridge that form no part of the claimed design. The broken lines showing the insertion tool in FIG. 8 illustrates environmental structure that forms no part of the claimed design.

1 Claim, 5 Drawing Sheets
